(57) **CLAIM**

The ornamental design for a bezel for an automotive lighting element, as shown and described.

DESCRIPTION

FIG. 1 is a perspective front view of a bezel;
FIG. 2 is a front view of the bezel;
FIG. 3 is a rear view of the bezel;
FIG. 4 is a right side view of the bezel;
FIG. 5 is a left side view of the bezel;
FIG. 6 is a top view of the bezel;
FIG. 7 is a bottom view of the bezel;
FIG. 8 is a perspective view of the bezel installed in an automotive lighting element;
FIG. 9 is a front view of the bezel installed in the automotive lighting element; and,
FIG. 10 is a side view of the bezel installed in the automotive lighting element.
The broken lines form no part of the claimed design.
